The ornamental design for a spacer with bracket, as shown and described.

DESCRIPTION

FIG. 1 is a front, top and left side perspective view of a spacer with bracket showing our new design;
FIG. 2 is a rear, top and right side perspective view thereof;
FIG. 3 is a front view thereof;
FIG. 4 is a rear view thereof;
FIG. 5 is a top plan view thereof;
FIG. 6 is a bottom plan view thereof;
FIG. 7 is a left side view thereof; and,
FIG. 8 is a right side view thereof.
The broken lines depict portions of the spacer with bracket that form no part of the claimed design.
